INTERNAL-COMBUSTION ENGINE.

1,327,202.

Specification of Letters Patent.

Patented Jan. 6, 1920.

Application filed August 6, 1917. Serial No. 184,694.

To all whom it may concern:

Be it known that I, FREDERICK M. GUY, a citizen of the United States, residing at the city of Jackson, county of Jackson, and State of Michigan, have invented certain new and useful Improvements in Internal-Combustion Engines, of which the following is a full and complete specification.

My invention relates especially to improvements in the valves employed in internal combustion engines to control the ingress and egress of the gases.

One of its objects is to provide a rotary valve which can be perfectly timed so that its intake and exhaust ports will open and close in such relation to the stroke of the piston, as to give the highest efficiency for said engine.

Another object is to provide a valve with ports which facilitate the ingress and exhaust of gases, with the least possible retardation.

Another object of my invention is to provide a valve for high speed engines, which will operate at a low enough speed to be commercially practicable and overcome defects found in former rotary valves.

Another object of my said invention is to provide by special construction means for reducing the friction on rotary valves caused by the pressure of the gases during the compression and explosion strokes of the piston, to such a low amount as not to unreasonably wear said valve, or interfere with its use with high speed engines.

Another object of my said invention, is to provide means for cooling the valve seat by the intake gas and for pre-heating said gas coming into said engine before it enters the cylinder, and facilitate its combustion.

Another object of my said invention is to so proportion the intake and exhaust ports to the stroke of the engine as to attain the highest efficiency in its operation at high speeds.

I am aware that others have constructed and used rotary valves in the operation of internal combustion engines, but heretofore they have not been practicable on high speed engines such as automobile engines, on account of the friction and wear of said valves when operating at high speed.

I attain the foregoing objects, and others

hereinafter set forth, by means of the special construction shown in the accompanying drawings, in which.

Figure 1 is a longitudinal sectional view of an internal combustion engine of the usual type, having my improved valve shown therein.

Fig. 2 is an end elevation, parts being omitted to illustrate the interior arrangement of the gearing.

Fig. 3 is a detail view of the valve seat showing the ports and cored out portions thereof.

Fig. 4 is a detail view of the valve showing the ports therein.

Fig. 5 is a section view of the ports in the valve and valve seat, showing the beveled sides thereof.

Similar letters and numerals refer to similar parts throughout the several views.

In illustrating my said invention, I have preferably shown it as adapted to a four cycle automobile engine as in general use in which a cylinder 1 of usual construction has a reciprocating piston 2 adapted for operation therein. The piston 2 is connected by the usual crank with the crank shaft (not shown) and rotates it whenever operated by the explosion of the gases in the cylinder head in the usual way.

In the cylinder head 3 I have provided a circular valve seat 4, and within the area of said valve seat I have provided the four intake ports *a*, *b*, *c* and *d* and the four exhaust ports *e*, *f*, *g*, and *h*. The intake ports extend from the chamber 10 (connected with the carburetor not shown) through the valve seat and thus connect through the ports in the valve hereinafter described, with the cylinder. The exhaust ports connect the cylinder, through the valve ports, and the valve seat with the exhaust chamber 11. I have preferably spaced these ports equi-distant about the center of said seat, and have constructed them with inner and outer dimensions corresponding to arcs, and the sides of said ports corresponding to radii. I have further beveled the sides of said ports, as shown, to produce the "venturi" opening as illustrated in Fig. 5 the purpose of which is more particularly described hereinafter.

Between the several pairs of intake and exhaust ports in the valve seat, I have cored

out portions of the face of the valve seat at 9, to a depth of $\frac{1}{16}$ inch or more for a purpose hereinafter explained.

Through the central portion of the valve seat 1 I have bored the hole 12 to form a journal for the valve stem 5 which rotates therein.

The valve member 6 is circular, and mounted upon the stem 5 as shown, and is slightly less in diameter than the surface of 10 the valve seat and is ground to form a gas tight joint when seated upon said valve seat, and is designed to rotate in contact therewith. I have shown four ports *i*, *j*, *k* and *l* in said valve, which are approximately the 15 same shape and size as the ports in the valve seat hereinbefore described, and are also spaced equi-distant about the center of said valve. It is designed that when the valve is rotated, the ports in the valve will register 20 with the four intake ports in the valve seat at one portion of its rotation, and with the exhaust ports in the seat at another portion of its rotation. I have beveled the sides of the ports in the valve, as shown in Fig. 5, 25 for the purpose hereinafter explained.

To operate the valve and valve stem, I have mounted the gear wheel 7 thereon as shown, and this in turn meshes with a pinion wheel 8, in operative connection with 30 the crank-shaft and operated thereby. In the design shown, I have preferably shown the gear and pinion wheels so proportioned that the gear wheel and stem rotate once every time the crank shaft is rotated eight 35 times. By this construction the valve is rotated one-sixteenth of a turn at every stroke of the piston, which I find sufficiently slow for practically all engines. The valve is so adjusted, that at every fourth stroke of the 40 piston the ports in the valve register over the exhaust ports in the valve seat, and at the succeeding stroke, they register over all of the intake ports in the valve seat. At the remaining two of the four strokes, the ports 45 in the valve register between the ports in the valve seat, and over the cored out portions 9, thus closing said valve against ingress or egress of gas or air.

At 13 I have provided a ball bearing to 50 receive the end thrust and pressure upon the closed valve and stem during the compression and explosion strokes, thus reducing the friction of rotation during those strokes, and relieving the valve and valve 55 seat from undue wear caused ordinarily thereby. The valve seat member which is cylindrical, forms a cylinder head, and the ball bearing which is arranged at the outer end of the valve stem is interposed between 60 the same and a cap, which is mounted upon the valve seat member. The gearing is located within the cap and the shaft on which the pinion is mounted is located in and extends longitudinally of one of the walls of 65 the cylinder.

Heretofore it has been impossible to use the rotary valve in engines operating at high speed, as the speed at which the valve was required to operate was too high and required too much power, and the friction caused by the pressure of the compressed and exploded gases during half of the rotation was so great that it wore the valve out too rapidly, and made it commercially impracticable.

It will be seen that in my invention I have provided a valve which rotates at a much slower speed than the crank shaft. While I have shown it as operating at one-eighth that of the crank shaft, it will be apparent, 70 that the same style may be varied so as to operate it at one-twelfth, or one-sixteenth engine speed, by changing the sizes and number of teeth in the gear and pinion wheels driving it, and by varying the number of port openings in the valve and valve seat.

It will also be seen that I have greatly reduced the friction by coring out portions of the valve seat at 9, and by this construction, 75 when the valve is closed during the compression and explosion strokes at which the greatest pressure is developed, the compressed gases are permitted to enter this cored out space in the rear of the valve, and thus exert an equal pressure on the back of the valve, balancing the pressure on the face of the valve over an equal area. While in practice I find that a cored out portion equal to one-third of the area will produce satisfactory results, it will be apparent from the drawings that nearly fifty per cent. of the area of the valve seat may be cored out if it is desired, or becomes necessary in any particular case to thus further reduce the pressure against the face of the valve.

It will also be seen that the ball bearing designed to carry the end thrust of the valve and stem receives a large part of the pressure, and thus reduces the friction, and the power necessary to rotate said valve, and the consequent wear, and also minimizes the variation in the wear which ordinarily would be caused by the variation in pressure at different portions of the rotation.

The cored out portions of the valve seat perform a further useful purpose during the intake stroke, as the suction caused by the stroke of the piston, withdraws portion of the air or gas in this space in the rear of the valve, and tends to form a vacuum. As the pressure consequently is less in the rear of the valve than on the face, the difference will hold the valve on its seat, resisting the pressure of the incoming gases and their tendency to lift the valve from the surface of the valve seat.

In high speed engines where the intake, and exhaust of the gases occur so many times in a minute, it is essential that the

ingress and egress of the gases should be facilitated in every way possible. By employing four or more intake and exhaust ports, equi-distant the gases are drawn in or exhausted at four different portions of the valve seat area at one and the same time, and the retardation is only one-fourth what it would be if the gases were required to pass through one port. Again, by employing the "venturi" form of port, with the beveled sides, the gases have the largest possible opening to pass into when they first start, and while their momentum is at the lowest, and after they have passed the throat of the valve port, the form of the port permits the gases to expand, and thus reduce the pressure, so that they do not tend to hold back the gases which are following in through the same port. This construction greatly facilitates the quick and rapid intake and exhaust of the gases, and greatly increases the efficiency of my said valve.

It will further be seen that I have greatly facilitated the operation of my said engine, by placing the intake gas or fuel chamber directly between the cylinder, and the exhaust chamber 11. By this construction, the fresh fuel gas tends to cool off the cylinder, and on the other hand the cylinder on one side, and the exhaust chamber on the other pre-heat the fuel gas, so as to make it lighter, and more fluid, and more readily drawn within the cylinder, and at the same time, the temperature is high enough to greatly facilitate the combustion of the gas, and is a great assistance in winter to overcome the weather difficulties.

In the construction of my said valve and ports, I have given great care to the proportion of the rotation of the valve which is required to give the highest efficiency to the operation of the engine, and I find, as shown in my illustrations, that the most efficient operation is attained when I give 16 $\frac{2}{3}$ degrees to the explosion stroke of the engine; 28 $\frac{2}{3}$ degrees to the exhaust stroke; 23 $\frac{2}{3}$ degrees to the intake stroke; and 20 $\frac{2}{3}$ degrees to the compression stroke.

Having thus described my invention, what I claim and desire to secure by Letters Patent, is the following:

1. In an internal combustion engine, the combination of a cylinder; a reciprocating piston within said cylinder; multiple intake ports and multiple exhaust ports in the cylinder head; a rotary valve having multiple ports connected with and operated by the piston; cored out pockets between the ports in the cylinder head arranged to expose the inner face of the valve to the pressure of the gases on the compression and explosion strokes to equalize the pressure on the said valve, substantially as shown and for the purposes described.

2. In an internal combustion engine, the combination of a cylinder; a reciprocating piston; a piston controlled rotary valve in the cylinder head; a valve seat in the cylinder head; intake ports in the valve seat; exhaust ports in the valve seat; corresponding ports in the valve adapted to cover and uncover said ports; cored out portions between the ports in said valve seat arranged to expose the inner face of the valve to the pressure of the gases on the compression and explosion strokes to equalize the pressure on the said valve, substantially as shown and for the purposes described.

3. In an internal combustion engine, the combination of a rotary valve rotatably mounted on a stem journaled in a bearing in the cylinder head; a gear wheel on said stem; means for operating said gear wheel synchronous with the piston stroke; a valve seat; multiple intake ports and multiple exhaust ports in said valve seat; cored out pockets between said ports in the valve seat arranged to expose the inner face of the valve to the pressure of the gases on the compression and explosion strokes to equalize the pressure on the said valve; multiple ports in the valve adapted to cover and uncover said intake, exhaust ports, and cored out pockets; at different portions of its revolution, substantially as shown and for the purposes described.

4. In an internal combustion engine, the combination of a cylinder; a valve seat in the cylinder head; a valve stem journaled centrally of said valve seat; a gear on said stem; a valve on said stem; a reciprocating piston within the cylinder; means connected with said piston for operating said gear, stem and valve synchronous with said piston according to a predetermined ratio; multiple intake ports in the cylinder proportioned to said ratio; multiple exhaust ports in the cylinder also proportioned to said ratio; multiple ports in the valve likewise proportioned to said ratio; said valve ports being so disposed about the center as to uncover all of the intake ports at a certain portion of its revolution; to uncover all of the exhaust ports at other portions of its revolution; and to cover all of said ports during the remaining portion of its revolution; cored out pockets between the ports in the cylinder connected with the cylinder and arranged to expose the inner face of the valve to the pressure of the gases on the compression and explosion strokes to equalize the pressure on the said valve.

5. In an internal combustion engine, a valve seat in the cylinder head; a valve stem journaled in the cylinder head centrally of said valve seat; four ports in said valve seat and head equi-distant connecting said cylinder with the fuel gas chamber; four ports in said valve seat and cylinder-head

- equi-distant connecting the cylinder with an exhaust chamber; cored out pockets between said ports; a valve mounted to rotate on said stem in contact with said valve seat, 5 said pockets being arranged to expose the inner face of the valve to the pressure of the gases on the compression and explosion strokes to equalize the pressure on the valve, four ports in said valve equi-distant; means 10 for operating said valve to successively uncover the exhaust ports, the intake ports and the pockets in the valve seat at predetermined portions of its revolution, substantially as shown, and for the purposes described. 15
6. In an internal combustion engine, the combination of a cylinder, a piston operating within the cylinder, a cylindrical valve seat member secured to the cylinder at the explosion end thereof and constituting a cylinder head and provided with a valve seat and having multiple intake and multiple 20 exhaust ports, a rotary valve fitted against the valve seat and having multiple ports, a valve stem connected with the rotary valve and extending through the said valve seat member, a shaft extending longitudinally of the cylinder and located within one of the walls thereof, a cap mounted on 25 the valve seat member, and gearing arranged within the cap and located at the outer face of the valve seat member and connecting the valve stem with the said shaft.
7. In an internal combustion engine, the combination of a cylinder, a piston operating within the cylinder, a cylindrical valve seat member secured to the cylinder at the explosion end thereof and constituting a cylinder head and provided with a valve 30 seat and having multiple intake and multiple exhaust ports, a rotary valve fitted against the valve seat and having multiple ports, a valve stem connected with the ro- 35
- 40

45 tary valve and extending through the said valve seat member, a shaft extending longitudinally of the cylinder and located within one of the walls thereof, a cap mounted on 50 the valve seat member, gearing arranged within the cap and located at the outer face of the valve seat member and connecting the valve stem with the said shaft, and an end thrust ball bearing interposed between the outer end of the stem and the said cap.

8. In an internal combustion engine, the combination of a cylinder, a piston operating 55 in the cylinder, a detachable head for the cylinder comprising at its lower end a valve seat member having a plurality of intake ports and a plurality of exhaust ports, a rotary valve seating on the lower 60 surface of said valve seat member and having a plurality of ports for opening and closing said exhaust and intake ports, a common exhaust passage formed in said cylinder head and leading out from same, and 65 individual exhaust passages leading from the exhaust ports to said exhaust passage, a chamber immediately above the valve seat member extending over substantially the entire area of the same and communicating 70 with the several intake ports in the valve seat and constituting an intake passage for the fuel mixture which also serves as a cooling chamber for the valve and valve seat due to the flow of the relatively cool intake 75 mixture over substantially the entire upper surface of said seat.

In testimony whereof, I have signed the foregoing specification, in the presence of two witnesses, at the city of Jackson, Michigan, this 31st day of July, 1917.

FREDERICK M. GUY.
